COMBINED PRESSER FOOT AND SEWING GAGE

Carmen L. Tanner, 701 Colusa Ave.,
El Cerrito, Calif. 94530

Filed June 7, 1971, Ser. No. 150,891

Term of patent 14 years

Int. Cl. D15—06

U.S. Cl. D70—2 B

FIG. 2

FIG. 3

FIG. 4

FIG. 5

FIG. 1

FIG. 6

FIG. 1 is a perspective view of a combined presser foot and sewing gage showing my new design;

FIG. 2 is a plan view thereof with the shank connecting member removed;

FIG. 3 is a bottom view thereof;

FIG. 4 is a side elevation taken from the position indicated by line 4—4 of FIG. 2;

FIG. 5 is a front elevation taken from the position indicated by line 5—5 of FIG. 4; and

FIG. 6 is a rear elevation taken from the position indicated by line 6—6 of FIG. 4.

I claim:

The ornamental design for a combined presser foot and sewing gage, as shown.
